LIQUID FUEL BURNER OF THE PRESSURE TYPE

Hugh Charles Hebard, Greenford, England

Application February 27, 1945, Serial No. 579,987
In Great Britain February 18, 1944

3 Claims. (Cl. 158—120)

1

This invention relates to lamps and stoves of the kind adapted to burn oil or spirit under pressure and to the kind wherein the fuel is fed from a reservoir through a vaporiser heated during operation by the burner or by a mantle carried by the burner.

In oil burning devices of the kind described it is essential to provide a means such as pricker or needle for cleaning the vaporiser orifice which is necessarily of small diameter and therefore prone to be choked by carbon. Devices of this kind are much more effective if they are situated inside the vaporiser, since any obstructing foreign matter is then expelled from the vaporiser orifice in the direction of flow and not against it.

Devices previously employed for cleaning the vaporiser orifice of a pressure burner from within have made provision for raising the cleaning needle inside the vaporiser but although means were proposed whereby pressure leakage at the point where the operating mechanism entered the reservoir was positively prevented, the assembly was complicated.

The object of the present invention is to provide an improved and simplified means for cleaning the vaporiser orifice of a pressure burner from within which does not suffer from the disadvantage mentioned above and does not necessitate the use of packed glands under pressure during the burner operation.

According to the invention a pressure burner for liquid fuel is provided wherein a cleaning needle carried by means fixed relatively to a fuel reservoir is disposed within a vaporiser tube flexibly connected to said reservoir and capable of depression to cause the cleaning needle to enter the orifice of the burner nipple.

According to one form of the invention a pressure burner for liquid fuel comprises a cleaning needle fixed at its base within a fuel reservoir above which the burner is supported, a vaporiser tube mounted around said cleaning needle and carrying the burner nipple at its upper end, means for depressing said vaporiser tube to cause the cleaning needle to enter the orifice of the burner nipple and a flexible metallic bellows device which connects the said vaporiser tube to the reservoir and acts as a return spring after the tube has been depressed to clean the nipple orifice.

Reference will now be made to the accompanying drawings which illustrate a pressure lamp having therein a device constructed in accordance with the invention and in which:

2

Fig. 1 is an elevation partly in section of the lower portion of the lamp,

Fig. 2 is a sectional elevation of the upper portion of the lamp completing the illustration thereof in Fig. 1,

Fig. 3 is a sectional elevation of the adjusting mechanism for the vaporiser tube, and

Fig. 4 is a sectional plan taken on the line IV—IV of Fig. 3.

10 In the construction illustrated, the invention is shown as applied to a pressure lamp of conventional design which includes a fuel reservoir 1 having a filler cap 2 and upon which reservoir is mounted a lamp structure including a base or gallery 3 through which extends a bolt 4 by which the said gallery is secured detachably to the reservoir 1. From the upper portion of the said gallery 3 extend vertical rods 5 which support at their upper ends a hood 6 provided with apertures 20 7 for the escape of products of combustion. The gallery 3 also supports a lamp glass or chimney 8 whose upper end engages within the lower portion of the hood 6.

The fuel reservoir 1 is connected to the burner 25 components within the hood 6 by a vaporiser tube 9 which is adapted for slight vertical movement as hereinafter described. The lower end of the said tube terminates within a cylindrical casing 10 whose lower end is closed by a plug 11 formed

30 with perforations 12 which enable the fuel to enter the cylinder 10 and the lower end of the vaporiser tube 9. The upper end of the cylinder 10 depends from a socket 13 formed with a flange 14 at its upper end which is fixed in the mouth

35 of a circular opening 15 at the top of the reservoir 1. The entry of the vaporiser tube 9 to the reservoir is sealed by means of a flexible metallic bellows 16 whose lower end is fixed to the exterior of the said tube at 17 and whose upper end is se-

40 cured to a disc 18 held within the socket 13 by means of a screw-threaded plug 19 formed integral with a nut 20 to enable it to be inserted and removed.

45 Fixed within the nut 20 is a sleeve 21 having a flanged head 22 between which and the nut 20 is mounted a fixed sleeve 23 formed with a cam slot 24 whose shape is shown in Fig. 3. Surrounding the sleeve 23 is a movable sleeve 25 whose upper end is fixed to the vaporiser tube 9 by means of a transverse U-shaped pin 26 shown 50 in Fig. 3. In the sleeve 25 is fixed an operating handle 27 whose inner end projects through the sleeve and is provided with a roller 28 engaging the cam slot 24 so that as partial rotary movement is imparted to the arm 27 the effect of

the roller moving in the slot 24 is to raise or lower the sleeve 25 and vaporiser tube 9 according to the direction of movement of the arm 27. The lower portion of the gallery 3 is cut away at 29 to accommodate the above-described means for raising and lowering the vaporiser tube.

The upper end of the vaporiser tube 9 is fixed into a head 30 of larger diameter (see Fig. 2) which carries a coiled tube 31 extending around a burner 32 from which a mantle 33 depends. The upper end of the head 30 terminates in an orifice 34 formed in a nipple 35 detachable from the member 30. A cleaning needle 36 adapted to operate in the nipple orifice 34 extends completely through the vaporiser tube 9 and is secured centrally into the plug 41, as shown in Figure 1, by means of a nut 37. The nipple orifice 34 opens into a horizontal open-ended tube 38 to which air is admitted through apertures 39 in the hood 6 and through which passes centrally a mixing tube 40 whose upper end is curved and which communicates with the interior of the tube 38 immediately above the nipple orifice 34 so that air is induced into the mixing tube 41 by the exit of fuel under pressure from the nipple orifice 34. The products of combustion ascending from the mantle 33 pass around the tube 38 and escape through the outlets 7.

When movement of the vaporiser tube is effected by means of the arm 27 the entire vaporiser tube is moved downwards so that the upper end of the needle 42 enters the orifice 34. This operation is repeated as many times as may be necessary in order to cleanse the orifice, the bellows 16 operating as a return spring so as to restore the vaporiser tube to the position shown in Fig. 2 to enable operation of the lamp to proceed.

By means of the construction above described the vaporiser tube 9, rod 36 and cleaning needle 42 form a unit adapted to be readily detached from the reservoir 1, which operation can be simply effected by removal of the nut 20 from the position shown in Fig. 1, after the gallery and hood have been removed.

I claim:

1. In a pressure-operated liquid fuel burning device, the combination of a fuel reservoir, a vaporizing tube supported by said reservoir for axial movement relatively to said reservoir, an apertured burner nozzle carried by said vaporizing tube, a cleaning needle in said vaporizing tube and having fixed support from said reservoir, means for depressing said vaporizing tube and

thereby placing said cleaning needle in cleaning position in said nozzle aperture, the support for the base of said cleaning needle being within said reservoir and said vaporizing tube being mounted around said cleaning needle, and a resilient and flexible metallic bellows device connecting said vaporizing tube with said reservoir and tending to hold said vaporizing tube in its upper position.

2. In a pressure-operated liquid fuel burning device, the combination of a fuel reservoir, a vaporizing tube supported by said reservoir for axial movement relatively to said reservoir, an apertured burner nozzle carried by said vaporizing tube, a cleaning needle in said vaporizing tube and having fixed support from said reservoir, means for depressing said vaporizing tube and thereby placing said cleaning needle in cleaning position in said nozzle aperture, the lower end portion of said vaporizing tube being in said reservoir and extending towards the base thereof, an annular socket carried by the top wall of said reservoir around said vaporizing tube and providing for free vertical movement of said vaporizing tube in said socket, and a flexible metallic bellows device disposed around said vaporizing tube and having its lower end sealed to the exterior of said vaporizing tube and having its upper end fixed to said socket.

3. In a pressure-operated liquid fuel burning device, the combination of a fuel reservoir, a vaporizing tube supported by said reservoir for axial movement relatively to said reservoir, an apertured burner nozzle carried by said vaporizing tube, a cleaning needle in said vaporizing tube and having fixed support from said reservoir, means for depressing said vaporizing tube and thereby placing said cleaning needle in cleaning position in said nozzle aperture, the lower end portion of said vaporizing tube being in said reservoir and extending towards the base thereof, an annular socket carried by the top wall of said reservoir around said vaporizing tube and providing for free vertical movement of said vaporizing tube in said socket, a flexible metallic bellows device disposed around said vaporizing tube and having its lower end sealed to the exterior of said vaporizing tube and having its upper end fixed to said socket, a second tube depending from said socket and surrounding said vaporizing tube and said bellows device, a perforated plug at the lower end of said second tube, and a rod fixed at its lower end to said plug and carrying said cleaning needle at its upper end.

HUGH CHARLES HEBARD.
